(57) **CLAIM**

The ornamental design for a robot dog, as shown and described.

DESCRIPTION

FIG. 1 is a front, right and top perspective view of a robot dog showing my new design;

FIG. 2 is a rear, left and bottom perspective view thereof;

FIG. 3 is a rear, left and top perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a partial enlarged view taken from circle 10 in FIG. 1;

FIG. 11 is a partial enlarged view taken from circle 11 in FIG. 1;

FIG. 12 is a partial enlarged view taken from circle 12 in FIG. 1;

FIG. 13 is a partial enlarged view taken from circle 13 in FIG. 1; and,

FIG. 14 is a partial enlarged view taken from rectangle 14 in FIG. 4.

The dash-dash broken lines in the drawings depict the portions of the robot dog which form no part of the claimed design.

The dot-dash broken lines in the drawings depict the boundaries of the partial enlarged views that form no part of the claimed design.

1 Claim, 14 Drawing Sheets
